DESIGN FOR A CURTAIN OR THE LIKE

Max Sadinoff, Brooklyn, N. Y.

Application September 30, 1933. Serial No. 49,380

Term of patent 3½ years

To all whom it may concern:

Be it known that I, MAX SADINOFF, a citizen of the United States, residing at 1766 Union Street, in the Borough of Brooklyn, city of New York, county of Kings, and State of New York, have invented a new, original, and ornamental Design for a Curtain or the like, of which the following is a specification, reference being had to the accompanying drawing, forming a part thereof.

The figure is a plan view of a curtain showing my new design. The surface ornamentation has been only partially shown in detail, it being un-

derstood that the ornamentation continues over the outlined portion of the curtain. The broken away portion between the dotted lines shows the continuation of the design at the point of breakage.

I claim:

The ornamental design for a curtain or the like, as shown and described.

In testimony whereof I have signed this specification,

MAX SADINOFF.
